PATENTED SEPT. 27, 1904.

L. ANDERSON.

FEED VALVE FOR EXPLOSIVE ENGINES.

APPLICATION FILED SEPT. 29, 1902. RENEWED FEB. 26, 1904.

NO MODEL.

Fig. 1.

UNITED STATES PATENT OFFICE.

LARS ANDERSON, OF CHICAGO, ILLINOIS, ASSIGNOR OF ONE-HALF TO
WILLIAM A. KING, OF CHICAGO, ILLINOIS.

FEED-VALVE FOR EXPLOSIVE-ENGINES.

SPECIFICATION forming part of Letters Patent No. 770,731, dated September 27, 1904.

Application filed September 29, 1902. Renewed February 26, 1904. Serial No. 195,476. (No model.)

To all whom it may concern:

Be it known that I, LARS ANDERSON, a citizen of the United States, residing at Chicago, county of Cook, and State of Illinois, have invented certain new and useful Improvements 5 in Feed-Valves for Explosion-Engines, of which the following is a full, clear, and exact specification.

My invention relates to the means for supplying explosion-engines with the requisite 10 amount of fuel for each charge or explosion; and it has for its primary object to provide an improved and simple device for measuring the charge and positively depositing the same 15 in the explosion-chamber or other place where required.

Another object of my invention is to provide a device of this character which shall be 20 of such a nature that it may be readily adjusted automatically or by hand, as desired, whereby the speed of the engine may be governed; and a still further object of my invention is to provide an improved form of intake-valve which shall be simple and inexpensive in construction and through which the air may pass 25 for keeping the valve cool.

With these ends in view my invention consists of certain features of novelty in the construction, combination, and arrangement of 30 parts by which the said objects and certain other objects hereinafter appearing are attained, all as fully described with reference to the accompanying drawings, and more particularly pointed out in the claims.

35 In the said drawings, Figure 1 is a longitudinal sectional view of my improved valve. Fig. 2 is a cross-section thereof, taken on the line 2 2, Fig. 1. Fig. 3 is a detail sectional view on the line 3 3, Fig. 1; and Fig. 4 is an enlarged detail view of the plunger and a part 40 of its operating-stem, hereinafter described.

1 represents the cylinder-head, having an induction-passage 2 leading into the cylinder 3, or these parts may represent the walls of 45 an ordinary explosion-chamber commonly employed on this type of engine.

Secured to the head 1 is a valve-housing 4, having a neck 5, which communicates with the induction-passage 2. The interior of this

housing 4 is funnel-shaped, as shown in Fig. 50 1, and it receives a conical valve 6, which is also hollow, whereby air may pass into it through either end and thence enter the neck 5, which constitutes the outlet-port of the valve-housing, through side ports 7 8 in the 55 lower side of the valve 6. The valve 6 is held in place snugly against its seat in the housing 4 by two end caps 9 10, which are secured to the ends of the housing 4 in any suitable way, and between the ends of the valve and these 60 caps are preferably interposed antifriction-balls 11, whereby the valve may be held reasonably tight in the housing and at the same time free to revolve. When these antifriction-balls are used, it is desirable to let the balls into 65 grooves 12 in the ends of the valve and provide annular races 13, let into the inner faces of the caps 9 10, which are provided with set-screws 14, whereby the races may be adjusted 70 with relation to the valve for keeping the bearings tight. The caps 9 10 are provided with air-induction ports 15 16, respectively, whereby the inspiration stroke of the engine will draw air into the hollow valve and thence into the cylinder whenever the ports 7 8 in 75 5 the valve are in register with the port 5.

Between the ports 7 8 is formed in the valve 6 a measuring-cavity 16, which as the valve is oscillated alternately comes into register with a supply-port 17 and the outlet-port 5, thus 80 taking at each oscillation a charge of explosive liquid from the inlet-port 17 and conducting the same to and depositing it in the outlet-port 5, where it is caught by the strong currents of air entering the port 5 through 85 the ports 7 8 and converted into vapor as the mixture passes into the induction-port 2. The inlet-port 17 may be supplied with gasoline or other suitable combustible from any desired source by means of connection 18, and, 90 as shown in Fig. 2, the port 17 and this connection, for a part of its length at least, are turned upwardly, whereby the air trapped in the measuring-cavity 16 will rise out of the cavity into connection 18 when the cavity is 95 turned upwardly to communicate with the supply-port 17. In order that the valve may be thus oscillated, it may be connected to the

- moving parts of the engine (not shown) in any suitable way. In the example of the invention illustrated this is accomplished by a rocker-shaft 19, mounted in an extended bearing 20 on the cap 10 and having a head 21 removably seated in the end of the valve 6, the outer end of the rocker-shaft 19 being provided with a rocker-arm 22, pivotally secured to one end of a suitable connection 23, which 5 derives motion from any suitable source for rocking the shaft 19.
- In order that the capacity of the measuring-cavity 16 may be varied to suit the requirements of the engine, the cavity is provided 15 with a plunger 24, which is formed on one end of a bifurcated stem 25, preferably made larger in diameter than the plunger 24 and having its upper end arranged in and guided by a passage 26, formed in the opposite side of valve 6, said passage also constituting a means for the insertion of the plunger and its stem. Between the two sides of the bifurcation 25 passes a cylindrical rod 27, which is provided 20 with a beveled or inclined slide 28, whose edges engage in inclined grooves 29, formed in the opposed sides of the bifurcated stem 25, so that when the rod 27 is moved longitudinally in one direction the slide 28 will raise the plunger 24, and thereby increase the capacity of 25 measuring-cavity 16, and when moved in the opposite direction will decrease its capacity. The rod 27 is arranged in line with the axes of the valve 6 and shaft 19, and for the sake of sufficient support the inner end of rod 27 is 30 journaled in a bearing 30, bored in the inner end of shaft 19, while the other end of shaft 27 is mounted in an extended bearing 31, formed on cap 9, so as to revolve freely with the valve. Rod 27 may be thus actuated in 35 any suitable way either by hand or automatically by any of the automatic governors common in this art. In the drawings I have shown the outer end of the rod provided with two collars 32, whereby a shifting-lever 33, 40 may be connected thereto for shifting the rod as desired and while the valve is in operation. It is of course needless to say that this rod 33 may be connected to a governor on the engine.
- 45 Having thus described my invention, what I claim as new therein, and desire to secure by Letters Patent, is—
1. In a feed-valve for explosion-engines, the combination of a valve-housing having inlet-ports for air, and a combustible, and an outlet-port for the mixture, an oscillatory valve arranged in said housing, and having a passage therethrough communicating with said air-inlet port and a side port communicating 55 with said passage and adapted to register with said outlet-port, and a measuring-cavity adapted to alternately register with said combustible-inlet port and said outlet-port, substantially as set forth.
  - 60 2. In a feed-valve for explosion-engines, the

combination of a valve-housing having inlet-ports for air, and a combustible, and an outlet-port for the mixture, an oscillatory valve arranged in said housing, and having a passage communicating with said air-inlet port, 70 and a port communicating with said passage, and adapted to register with said outlet-port, a measuring-cavity formed in said valve and adapted to alternately register with said combustible-inlet port and said outlet-port, and 75 means for varying the capacity of said cavity, substantially as set forth.

3. In a feed-valve for explosion-engines, the combination of a valve-housing having inlet-ports for air, and a combustible, and an outlet-port for the mixture, an oscillatory valve arranged in said housing, and having a passage adapted to communicate with said air-inlet port, and a port communicating with said passage and adapted to register with said outlet-port, a measuring-cavity formed in said valve, and means for varying the capacity of 80 said cavity, comprising a rod arranged in line with the axis of said valve whereby it may be actuated while the valve is oscillating, substantially as set forth.

4. In a feed-valve for explosion-engines, the combination of a valve-housing having inlet-ports for air and a combustible, and an outlet-port for the mixture, an oscillatory valve 95 in said housing having an axial passage communicating with said air-inlet port, and a port communicating with said passage and adapted to register with said outlet-port, a measuring-cavity formed in said valve and 100 adapted to alternately register with said combustible-inlet port and the outlet-port, substantially as set forth.

5. In a feed-valve for explosion-engines, the combination of a valve-housing having an inlet-port for air, and an outlet-port, a hollow oscillatory valve arranged in said housing, and having communication with the atmosphere, a port formed in the side of said valve in communication with the hollow interior thereof, 105 and adapted to communicate with said outlet-port in the housing as the valve oscillates, and means for supplying a combustible to said inlet-port, substantially as set forth.

6. In a feed-valve for explosion-engines, the combination of a valve-housing having inlet-ports for air and a combustible and an outlet-port for the mixture, a hollow oscillatory valve arranged in said housing and having its interior communicating with said air-inlet port, and a side port in communication with its interior and adapted to communicate with said outlet-port, a measuring-cavity in said valve adapted to alternately communicate with said combustible-port and outlet-port, a plunger in said cavity, an inclined slide arranged in said valve, and operatively connected with said plunger for reciprocating the latter, and a rod connected with said slide and arranged in line with the axis of said 130

valve for operating the slide, substantially as set forth.

7. In a feed-valve for explosion-engines, the combination of a valve-housing having inlet-ports for air and a combustible, and an outlet-port for the mixture, a hollow oscillatory valve arranged in said housing and having a port, placing said air-inlet port in communication with said outlet-port via the interior of the valve, a measuring-cavity formed in the side of the valve and adapted to alternately communicate with said combustible-inlet port and said outlet-port, a plunger in said cavity, a bifurcated guide-stem on said plunger ex-

tending across the interior of the valve, and having grooves, an inclined slide arranged in the valve and engaging in said grooves, a rod arranged in line with the axis of the valve for operating said slide, a rocker-shaft having operative connection with one end of said valve, and into which shaft one end of said rod is journaled, and means for supporting said rod and shaft, substantially as set forth. 15
